UNITED STATES PATENT OFFICE.

NEWTON J. WIGGINTON, OF WINCHESTER, VIRGINIA.

GRADING MACHINE.

Application filed April 14, 1925. Serial No. 23,070.

My present invention relates to improvements in grading machines of the type employed in grading fruits, vegetables and similar articles. The machine of my invention has been reduced to practice and successfully operated as an apple grading machine, and I shall therefore for convenience of illustration and description hereinafter refer to it as an apple grading machine. Before proceeding with the description in detail of the various embodiments and uses of the machine, it is proper to say that in some or all respects my invention is applicable for use in grading various kinds of fruits and various kinds of vegetables.

The primary object of my invention is the provision of a portable and foldable implement which may be taken directly to the orchard or field, and with facility moved about from place to place for the convenience of the orchardist or farmer in grading fruits or vegetables. As here illustrated the machine is adapted for manual power in its operation and the operation of the machine is accomplished with a minimum supply of labor or attendants, but it will be understood that mechanical power may be utilized to drive the operating parts of the grading machine if desired.

To facilitate transportation or removal of the machine from place to place I have embodied therein a wheeled implement upon which other parts of the machine are adapted to be folded and stored in a compact arrangement, and means are provided for trundling or manually propelling the implement.

The different units or sections of the machine are interchangeable and provided with detachable hinged joints which enable the attendant to assemble the several units in operative relation with rapidity and convenience and after assembly the parts are so related as to afford a compact, smooth working, and efficient machine of this character by means of which the apples, or other articles to be graded, are passed through the machine and properly graded.

The capacity of the machine for grading various sizes of apples may be increased or decreased with relation to the machine as herein illustrated which machine is adapted to separate the apples into four grades.

The invention consists in certain novel

combinations and arrangements of parts as will hereinafter be more fully pointed out and claimed.

In the accompanying drawings I have illustrated one complete example of the physical embodiment of my invention wherein the parts are combined and arranged in accordance with one mode for the practical application of the principles of my invention, and as thus embodied the machine has successfully performed its required functions as a labor and time saving implement in efficiently and rapidly grading the apples.

It will be understood that one of the grading units may be dispensed with to reduce the capacity of the machine if desired, or one or more units may be added to the implement illustrated to increase the capacity of the implement, to suit various conditions or requirements.

In the accompanying drawings—

Figure 1 is a top plan view of the apple grading machine adapted for use in separating four grades of apples which are passed therethrough from the feed hopper at the left end, and the highest grade of apples discharged on the table at the right end of the implement.

Figure 2 is a vertical, longitudinal, sectional view of the machine of Figure 1 with parts broken away for convenience of illustration.

Figure 3 is a perspective view of the machine illustrating its use on irregular surfaces as in an orchard or on a hillside.

Figure 4 is a transverse vertical sectional view of the machine showing one of the transversely arranged delivery troughs.

Figure 5 is a sectional detail view illustrating the manner of supporting one of the detachable and adjustable discharge troughs or side tables.

Figure 6 is a perspective view depicting the machine units folded upon the main wheeled implement for transportation.

Figure 7 is an enlarged detail face view of the hinge or pivot joint at one side of the end discharge table.

Figure 8 is a transverse sectional view at line 8—8 of Figure 7.

Figure 9 is a view of a modified form of attaching or hinge plate for the end discharge table used on a machine of smaller capacity.

Figure 10 is a face view of one of the feed-hopper joint members, and Figure 11 is a top edge view showing one of the foldable joints between the feed hopper and the 5 wheeled section of the machine.

Figure 12 is a perspective view of a smaller grader in folded position.

Figure 13 is a detail view showing the hinged construction for the discharge table.

10 In the assembled machine of the drawings I provide for four grades of apples which are separated or graded by the action of endless, moving, grading belts of suitable or approved type, which have openings of 15 various sizes to permit passage of the apples to be graded, except the largest grade, and the machine is operated by a single attendant who stands at one side of the machine adjacent to the feed hopper at the 20 left end of the illustrations in Figures 1 and 3.

The main section or unit of the machine is a wheeled vehicle of proper size and 25 shape which has a rigid frame that includes a pair of lower longitudinally extending beams 1 and 2 spaced apart and rigidly attached to a pair of long legs 3, 3 that are adapted to rest or stand upon the ground, and a pair of shorter legs or posts 30 3' 3' are also fixed to these beams.

35 A pair of upper or top beams 4, 4 secured at the tops of the legs and posts complete the rectangular main frame which provides a strong and stable support for the 40 various units or sections of the machine when the latter are folded as indicated in Figure 6.

This main frame is provided with a transversely extending axle 5 having bearings 5' 45 on the lower long beams and a pair of spaced traction wheels 6, 6, are provided to support the main unit of the machine.

50 For propelling the wheeled implement manually I employ a transversely extending handle bar 7 which may be grasped by one or more men for trundling the implement. This bar is supported in a frame 8 attached at one end of the implement to the beams 1 and 2, and the frame is fashioned with a detachable collar as 9 which permits demounting of the handle bar if required.

55 For reinforcing the frames of the various units I employ diagonally extending metal straps or braces 10 which are bolted at their ends to the elements to be connected and these braces are used throughout the structure where required, to insure a stable and strong framework.

60 Above the main frame of the wheeled implement are fixed the side walls or boards 11 between which travel the working flights of the belt 12 for ciders and the succeeding belt 13 for grade A apples. The grading 65 belts are of the endless type, the belt 12 traveling over spaced rollers 14 and 14' on

the shafts 15 and 16, and the grade A belt passing over similar rollers 17 and 17' on the shafts 18 and 19.

The grading belts may be of standard or any approved type having openings of the proper size to permit apples to pass therethrough, it being understood that the ciders fall into the flexible transversely disposed trough 20 and the grade A apples into the table 21, in position beneath the belts to receive the apples, and discharge them laterally. These troughs are made up of slats the ends of which at one side of the machine are supported from a longitudinally extending bar 22 which is in turn supported from 80 the top bars of the frame by means of angle brackets 23, the lower free ends of the troughs being flexible and suspended at a lower elevation than the fixed supported ends to permit movement of the apples 85 without danger of bruising them.

For driving the grading belts I utilize a transversely disposed drive shaft 24 supported in journal bearings 25 on the side boards 11. The bearings for the several 90 shafts may be of any usual or suitable type, or bearing blocks of wood may be attached to the respective frames and provided with metal bushings or bearing sleeves in which the ends of the shafts are journaled.

95 The drive shaft is manually revolved by an attendant who uses the hand crank or crank handle 26 attached at the free projecting end of the shaft which is located in such position as to enable the attendant to turn the shaft and at the same time give attention to the feed of apples to the machine.

The driving shaft is provided with a driving sprocket 27 and sprocket chain 28 which latter chain passes over the driven sprocket wheel 29 on the shaft 16. A second sprocket wheel 30 on the shaft 16 transmits the power through the chain 31 to the wheel 32 on the shaft 19 and it will be apparent that the upper or working flights of the grading belts are moved in the same direction, to the right in Figures 1 and 2 to convey apples too large to pass through them. Aprons 33 are located in position to transfer apples from one belt to a succeeding one, and these aprons are pivoted or hinged transversely of the grading machine as at 34, and provided with curved or turned up lower edges 35 that may contact with the grading belt when the belt is moving forward in its normal direction. In case of accidental rear movement of the upper or working flight of the belt, the latter may pass freely under the apron and because of the presence of its turned up or curved edge the apron does not interfere with the belt.

100 At the front end of the machine a feed hopper 36 of usual type is provided, which has a pair of supporting legs 37 to stand 105 110 115 120 125 130

upon the ground and in addition is supported by a pair of transversely disposed pivot or stud bolts 38, one at each side of the hopper. These bolts are passed through bolt holes in the ends of the side boards 11 of the main unit which is provided with reinforcing metal straps or plates 39 riveted to the side boards, and through which the bolts pass. The side boards of the hopper 10 also have reinforcing plates 40 secured thereto as by rivets or bolts 41, and these side boards together with the plates 40 are fashioned with a pair of longitudinally extending slots 42 for the stud bolts 38 to project 15 through. When in operative position as in Figures 1 2 and 3 the bolts form supports for the inner end of the hopper, and when the hopper is to be folded upon the main unit, as in Figure 6, these bolts form the 20 pivots or hinges, for the swinging movement of the hopper, the slots providing for a necessary lost motion or movement in the folding action. The slots 42 also permit the receiving table or hopper to readily adjust 25 itself to any irregularities on the surface of the ground upon which the implement is erected, the slot arrangement taking the strain off of the hinged connection.

The apples are transferred from the receiving table 36 to the belt 13 over an apron or gate 14 which is hinged at 36' on the receiving table to overlap the gap between the receiving table and the grading unit. Should an apple become entangled in the 30 belt and be carried up over the roller 14, the hinged gate will be lifted thereby to permit passage of the apple and prevent obstruction to the belt. The smallest fruit or ciders fall through this belt to the trough 20, and from this trough the ciders pass to the side table 43 from which the ciders are directed and gathered as desired. The side table is supported transversely of the grading machine and is adjustable for the purpose of guiding the ciders.

A pivoted brace bar 44 hinged at its underside supports the outer end of the chute by resting on the top edge of the beam 1, and the inner end of the chute is provided 50 with a pair of side plates or straps 48 each having a notch 46 in its upper edge, the construction being similar to that shown in Figure 5. A pair of rack plates 45 having notches 46 are attached to a pair of upright 55 posts 47, one at each side of the side table and secured to the top and bottom beams of the main frame. A removable supporting bar or rod 49 disposed longitudinally of the machine is adapted to rest in a complementary 60 pair of notches in the rack plates, and the supporting or side plates 48 of the side table rest upon the rod to afford a support for the table. This construction is shown specifically in Figure 5 and is used in the several 65 side tables employed in connection with the

grading machine whereby the side tables may with facility be attached or adjusted to desired position for use, and when not required may with facility be detached from the grading machine.

In Figure 2 an added section or unit is indicated as a whole by the numeral 50 and provided with side walls 51 as guides for the apples. This section is interposed next to the main section or unit and is provided with a roller 52 and a second roller 53, and a third grading belt 54 having openings or rings therein larger than the rings of the grade A belt 13. The respective rollers 52 and 53 are provided with shafts 55 and 56 journaled in bearings of suitable type, and these shafts and rollers are driven from the shaft 19 through the sprocket wheel 57 thereon. A chain 58 passes over the sprocket wheel 59 on the shaft 56 for conveying power supplied from the operating shaft 24.

It will be understood that the power transmission mechanism may be varied, and located in suitable or approved positions on the various sections or units for different purposes, and while I have shown a manually operated chain drive for the transmission of power it will be obvious that other forms and arrangements of power transmission mechanism may be used.

The added section or unit 50 which supports these rollers for the grade B apples includes a rectangular frame having a pair of longitudinally extending top bars 60 beneath which a chute 61 for the grade B apples is supported in manner similar to the two chutes 20 and 21 previously mentioned.

This frame also includes four corner posts 62 and it is braced and fashioned as a rigid structure which at one end is adapted to 105 rest and be supported upon a pair of angle plates 63 attached at the inner sides of the long beams 1 and 2. The lower ends of two of the posts 63 rest upon these plates to support the added frame and in addition it is 110 detachably hinged on the main section by means of perforated side plates or metal straps 64 hinged on the ends of the shaft 19. In this manner the added frame section may 115 with facility be incorporated in the grading machine for use and supported therein as one of its component units, and it may with equal facility be detached therefrom if not wanted. The added frame or unit 50 may 120 be folded on the shaft 19 as a hinge, to the position shown in Figure 6 where it has been turned up and over the main section for transportation of the machine.

A laterally projecting table 65 is provided 125 for the grade B apples which are received from the trough 61 and this side table 65 is readily detached from or attached to the machine. In Figure 5 it will be seen that the side table is equipped with a pair of metal side plates 66 each having a notch 67,

and two of the posts 62 are provided with complementary rack plates 68 having notches 69. The removable supporting rod 70 is supported between alined notches of these two plates 68 and the table plates 66 through their notches 67 are supported on the rod. At the outer end of the table a hinged and foldable supporting leg 71 is connected at the under side of the table and adapted to 10 rest upon the ground for the support of the table.

In Figure 6 another removable supporting rod is shown at 70' resting in a rack plate 68' which may be used for the support 15 of a table for the grade A apples, it being understood that the several removable tables for the various grades of apples are readily detachable and adjustable and supported in similar manner.

20 At the right end of the machines in the drawings the discharge of packing table 72 is arranged, and as shown in Figure 2 it is partially supported on a hinged and foldable leg 73 resting on the ground, and 25 hinged at 73' to the packing table.

This discharge or packing table may be of usual type and receives the apples, which are too large to pass through any of the grading belts, from the belt 54 and over roller 53, as they pass down the apron 74.

In Figures 7 8 and 9 the joint between the packing table and the adjoining section is illustrated. At each side of the packing table a metallic strap or plate 75 is attached and its free end provided with a notch 76 which is adapted to fit over a shaft, as 35 56, for the support of the packing table in addition to the hinged leg 73. In connection with the detachable notched side plates

40 I utilize a detachable bearing plate 77, one adapted to slip over each end of the shaft 56, and each provided with a flange 78 to suspend it from the top edge of the side plate 75. This construction provides a secure and rigid connection between the packing table and the section 50, which may quickly be disconnected when the bearing plates 77 have been removed, and it is desirable to detach the packing table from the 45 unit 50. In some instances the packing table is folded upon the main section of the machine, and when such is the case an auxiliary bearing plate or bar 79 is used. This auxiliary bearing bar is provided with a curved bearing notch 80 in one edge complementary to the notch 76 in the side plate and the auxiliary plate may be swung into operative position on the pivot bolt 81 after the removable bolt 82 has been loosened and removed 50 to permit it. As seen in Figures 7 and 8 the auxiliary bearing bar is idle and is fastened to the side plate 75 by the rivets 81 and bolt 82, but when the packing or discharge table is to be located in foldable 55 arrangement with respect to the implement,

this auxiliary bearing bar is brought into use, and the bolt 82 is located in the bolt hole 83 of the side plate.

In some instances the unit 50 may be disconnected from the grading machine and the 70 packing table of course disconnected from this section 50. Where a grader of smaller capacity, say for separating three grades of apples, is desired, the section or unit 50 may be omitted and the packing table then 75 is pivoted on the shaft 19 of the main unit said shaft taking the place of the shaft 56 in Figure 7. In such instance the auxiliary bearing bar 79 is brought into use and the packing table may be folded upon the implement in place of the unit 50 in Figure 6. In Figure 9 a modified form of side plate 84 is shown with a round bearing hole 85 which may be used as a permanent bearing and connection for the foldable packing 85 table on the small grading machine.

From this description taken in connection with my drawings it is believed the construction and operation of the grading machine will be apparent. In assembling the machine for use on uneven ground or irregular surfaces one or more wedges W may be used if necessary to level the machine, and as seen in Figure 3 one of the wheels is removed and a jack J is used beneath one of 95 the long beams as 1 to support the machine at this point instead of using the wheel 6 which is removed to make room for the ciders chute 43.

Guide blocks as 86 are located at suitable 100 points at the inner sides of the side walls of the units to direct and guide the apples outwardly from the side walls to assure their proper relation to the grading openings in the belts. The grading belts may be of any well known or standard type and as illustrated the three belts have openings respectively of $2\frac{1}{4}$, $2\frac{1}{2}$ and $2\frac{3}{4}$ inches in diameter, but it will be understood of course that belts with openings of other 105 diameters or shapes may be used in the grading machine. The apples may be sorted in usual manner at the various tables by attendants, one man being required for both 110 feeding and operating the grading machine.

Suitable bearings are provided for the shafts, one form of inexpensive but efficient journal bearing being the use of a metal bearing sleeve or bushing set in the bore of a wood bearing block which is supported 115 on the frame. I do not however confine myself to the use of any specific form of journal bearing. The bearing sleeve may be of brass with its ends expanded to secure it in the box or block and such a bearing is preferable to the usual wood bearing or journal member which is subject to expansion or contraction under differing weather conditions.

Various accessories and meritorious features are used in connection with the ma- 120 125 130

chine, as for instance the sections or units are provided with rounded shields as R adjacent to the rollers to prevent the apples from falling over the side boards as they 5 approach or pass around the upper rollers of the various belts.

Where the ground surface of the orchard or field is inclined or hilly the grading machine is set up with one end pointing down 10 hill. In such case the side tables extending laterally from the grading machine may readily be adjusted by means of the rack plates and their supporting bars or rods as 68 and 70.

15 The beams 1 and 2 as seen in the drawings are provided on their under edges adjacent to the wheels with beveled faces 1^a and 2^a. Either of the beams may be used in the absence of a wheel, for levelling the grader 20 in connection with a jack as J, and the proper adjustment may readily be secured by placing the jack at the required point on the beveled edge of the beam for this purpose.

25 On the inner faces of the opposite flared side walls of the receiving table or hopper 36, I provide notches or other receptacles as 24' to receive the respective ends of the operating shaft 24 when the receiving table 30 is folded over the main section, and this arrangement of parts it will be apparent prevents lateral vibration or movement of the table when in folded position as in Figures 6 and 12.

35 To secure the intermediate grading section or unit 50 against lateral movement or vibration when folded over the main section and receiving table as in Figure 6 the front wall of the receiving table is provided with 40 spaced cleats 51^a between which the side boards of the folded section are retained as they rest upon the wall of the receiving table.

Having thus fully described my invention 45 what I claim as new and desire to secure by Letters Patent is—

1. The combination in a portable grading machine of a main vehicle section, a feed hopper hinged thereto and adapted to fold 50 thereon and a support for the free end of said hopper, said hopper having means to permit vertical adjustment at its sides relative to the main section, a discharging table at the opposite end of said main section and 55 adapted to fold thereon, and means for supporting the free end of said discharging table.

2. The combination in a grading machine with a main vehicle section, of a removable 60 section hinged at one side of the main frame and adapted to fold thereon and means for supporting the free end of the removable section on the main section, a detachable section hinged at the opposite side of the 65 main section and adapted to fold thereon,

and means for supporting the free end of said last mentioned section.

3. The combination in a portable grading machine with a wheeled main section, of a foldable hopper hinged to said section and 70 a foldable discharging table pivotally supported therefrom, whereby said hopper and table may be folded upon the main section, and means for supporting the free ends of said hopper and discharging table in operative position.

4. The combination in a portable grading machine with a wheeled main section, of a foldable hopper hinged at one end of the section and supporting legs for the free end 80 of said hopper, a hinged detachable discharging table, and a foldable supporting leg for the free end of said table whereby the hopper and table may be folded to inoperative position upon the main frame. 85

5. The combination in a portable grading machine with a wheeled main section, of sets of rollers and endless grading belts supported in said section and means for operating the belts, a foldable hopper hinged at 90 one end of said section and means for supporting the free end of the hopper, a hinged, foldable and removable section located at the opposite end of the main section and means for supporting the free end of this 95 last section on the main section.

6. The combination in a portable grading machine with a wheeled main section, of sets of rollers and endless grading belts and means for operating said belts, a foldable 100 hopper hinged at one end of said section and a supporting leg for its free end, a foldable discharging table hinged at the other end of the main section and a foldable leg for supporting the free end of said table whereby said hopper and table may be folded to inoperative position on the main section. 105

7. The combination in a portable grading machine with a main section comprising a frame having a pair of lower beams, a handle carried by said beams, an axle supported on the beams and wheels thereon, and foldable component sections of the grading machine hinged at opposite ends of said frame with means for supporting the free 110 ends of said foldable sections.

8. The combination in a portable grading machine with a main wheeled section and a foldable feed hopper hinged at one end thereof, of a grading section hinged at the other end of said wheeled section with its free end supported thereon, a discharging table detachably connected to said grading section and means for supporting the free end of said table. 120

9. In a portable grading machine the combination with a main vehicle section and a foldable feed hopper hinged at one end thereof, of a grading belt, its rollers, shafts and means for operating the belt, a grading 125 130

section hinged on one of said shafts at the opposite end of the main section and means on the main section for supporting the free end of said grading section, and a grading device carried by said grading section and actuated from the first belt-mechanism.

10. The combination in a portable grading machine with a main wheeled section of a feed hopper having longitudinal slots in its opposite side walls, pivot bolts fixed to the main section and occupying said slots, and supporting legs on said hopper for the free end thereof.

11. In a portable grading machine the combination with a supporting section having an operating shaft therein, of a detachable discharging table having side bearing plates for the shaft, said plates having notches, and detachable bearing plates suspended on said side plates for completing the bearing for said shafts.

12. In a grading machine the combination with a supporting section and a shaft therein, of a detachable discharging table having side plates notched to engage said shaft, a removable bearing bar and bolts for retaining said bar in operative position.

13. The combination in a grading machine with a main section including a pair of longitudinal beams, supporting posts, and selectively removable wheels supported from said beams, of beveled faces on the lower edges on said beams whereby a jack may be used in co-action with said faces for leveling the machine.

14. The combination in a foldable grad-

ing machine of a main wheeled section including a pair of longitudinal beams, a pair of wheels, a pair of supporting posts spaced from said wheels, a transverse handle-frame connecting the free ends of said beams, and a handle supported in said handle-frame.

15. The combination in a foldable grading machine of a main vehicle-section, a receiving table hinged at one end of the section and adapted to fold thereon, a section of the machine hinged at the other end of the main section, co-acting means on the main section and receiving table for preventing lateral movement of the folded receiving table, and co-acting means on the receiving table and foldable section for preventing lateral displacement of the latter section.

16. The combination in a foldable grading machine of a main wheeled section, a receiving table hinged at one end of the main section and adapted to fold thereon, operating mechanism for the machine including an operating shaft adapted to engage socket members on the receiving table when the latter is folded over the main section, a section of the machine hinged at the other end of the main section, and spaced cleats on the receiving table for engaging said last mentioned section when folded to position over the main section.

In testimony whereof I affix my signature.

NEWTON J. WIGGINTON.
